UNITED STATES PATENT OFFICE.

WILLIAM H. ROSE, OF JERSEY CITY, NEW JERSEY.

CONTAINER.

1,409,412.

Specification of Letters Patent. Patented Mar. 14, 1922.

Application filed January 29, 1919. Serial No. 273,785.

To all whom it may concern:

Be it known that I, WILLIAM H. ROSE, a citizen of the United States, and residing at Jersey City, Hudson County, State of New Jersey, have invented certain new and useful Improvements in Containers, of which the following is a specification.

This invention relates to the construction of large containers, particularly those used for shipping material in bulk. The containers to which the invention particularly applies are those having capacity of ten gallons and upwards, the larger sizes being adapted to contain from 1 to 2 barrels of material. These containers are usually made of sheet metal and of cylindrical form and the cylindrical wall, particularly, has a large area and is expensive to construct as well as expensive for material. My invention consists in constructing the ends of such containers of heavy sheet steel or other metal, as is now customary, and connecting these ends by a very light sheet of metal to form the cylindrical wall of the container. Such light metal is sufficient to prevent leakage and to exclude dampness and also has sufficient tensile strength to prevent separation of the heads or ends of the container. I give to the side wall the necessary lateral strength and stiffness by encircling it with a paper or pulp cylinder of considerable thickness. The combination of the thin metal side wall and the thick paper-board wall gives to the package greater strength than the usual metal wall and at less cost and the package preserves its attractive appearance because the side walls are not easily dented in handling, furthermore the paper-board exterior is a good base for decoration or for the attachment of labels. I preferably waterproof the paper-board by applying some suitable agent for this purpose, such as tar, paraffin, etc.

The invention is illustrated in the accompanying drawing which represents, partly in side view and partly in section, a container of the character described.

Referring to this drawing, 10 indicates the bottom, and 11 the top, of the container. The top 11 is shown as provided with a friction lid 12 of usual construction but any suitable top and bottom plates may be used provided they are of sufficient thickness.

The actual thickness in any case will depend upon the size of the package and the nature 55 of the goods to be shipped, the thickness of the metal being such as to produce a rigid container which will maintain its shape during use.

The ends 10—11 are connected by a 60 cylindrical metal wall 13 which is suitably connected with the margins of the top and bottom. As shown, the side wall has outwardly extending marginal folded flanges 14 and the margins of the top and bottom 65 are turned over these flanges and pressed tightly upon them as shown at 15. The side wall may be interlocked with the top and bottom plates in any wellknown or suitable manner. It will be evident, however, that 70 by making the side wall thin the flanging and turning of its edges 14 may be done with lighter machinery and much easier than if the wall 13 were as thick as the ends 10—11. A saving in the cost of manufacture is thus effected and it will be evident that a large saving is effected in the cost 75 of sheet metal for the side wall. Surrounding and protecting the side wall 13 is a heavy paper-board wall 16. This wall may 80 be formed on a mandrel in one of the usual machines for making paper tubes and cylinders and slipped on to the side wall 13 before the top 11 is applied thereto. This is the preferred method. I may, however, use 85 the body of the container as a mandrel and wind thereon paper properly treated with adhesive until the desired thickness is attained. In either case the paper-board wall 16 is constructed of sufficient thickness to 90 support laterally the metal side wall 13 and to support and space the heads, that is, to prevent any tendency to telescope or collapse the metal side wall. As previously stated the metal side wall 13 may be made of very 95 thin material, as it requires very little thickness to prevent leakage and on account of the large circumferential dimension of such side wall quite thin metal will have sufficient tensile strength to prevent the heads from 100 pulling apart.

Having thus described my invention what I claim and desire to secure by Letters Patent is:

A container having heads composed of 105 metal which is relatively thick and suf-

ficiently rigid to maintain the shape of the container during use and having a cylindrical side wall composed of relatively thin sheet metal suitably secured to the heads, 5 and a jacket of thick paper material surrounding and closely fitting the side wall, the metal side wall serving to connect the

heads and prevent leakage and the paper wall affording lateral strength and longitudinal stiffness and serving to protect and support the thin metal wall, for the purpose set forth.

In testimony whereof I affix my signature.

WILLIAM H. ROSE.
